ELECTRIC TOASTER

Filed March 21, 1932

Fig. 1.

Fig. 2.

Fig. 3.

resistance wires 22 wound on all of the strips, as shown, and returns to terminal pole 28, the wires being connected in circuit by rivets 29 which pass thru the several strips to hold them in assembled 5 position.

In this modification the elements are shown connected in the circuit in series parallel, the current being divided at the junctures of the 10 lowermost and intermediate lateral elements with the vertically extending side strip elements. This construction permits the employment of an even larger number of smaller micaceous pieces.

In either device, the heating unit comprising 15 evenly wound micaceous strips and the conducting supports therefor (14 or 27 and 28) constitute a sub-assembly which may be cheaply constructed and quickly mounted in the toaster frame to provide a very durable and efficient device at low cost.

20 Having thus described our invention, we claim as new:

1. An electric heating unit adapted for use in a bread toasting device comprising a pair of vertical conductors, a plurality of nonconducting 25 heat resisting strips each having an uninsulated resistance wire of different length evenly wound thereon to provide separate heating elements of

different heating capacities, said strips being supported adjacent their opposite ends by said conductors and arranged horizontally one above the other in the order of their heating capacities, and means connecting said resistance wires in circuit with said conductors and with each other. 80

2. An electric heating unit adapted for use in a bread toasting device comprising upwardly extending conducting means, a plurality of nonconducting heat resisting strips each having an uninsulated resistance wire of different length evenly wound thereon to provide separate heating elements of different heating capacities, said strips being supported adjacent their opposite ends by 85 said means and arranged horizontally one above the other in the order of their heating capacities, and means connecting said resistance wires in circuit with said conducting means and with each other. 90

3. The structure defined in claim 2; said upwardly extending conducting means comprising uninsulated resistance wires supported in wound relation on vertical strips of nonconducting heat resisting material to provide the unit with additional heating capacity. 95
